UNITED STATES PATENT OFFICE.

FRANK W. ROBINSON, OF READING, PENNSYLVANIA, ASSIGNOR TO THE NOLDE & HORST CO., OF READING, PENNSYLVANIA, A CORPORATION OF PENNSYLVANIA.

CIRCULAR-KNITTING MACHINE.

1,291,155.

Specification of Letters Patent. Patented Jan. 14, 1919.

Application filed August 4, 1917. Serial No. 184,866.

To all whom it may concern:

Be it known that I, FRANK W. ROBINSON, a citizen of the United States, residing at Reading, in the county of Berks and State 5 of Pennsylvania, have invented certain new and useful Improvements in Circular-Knitting Machines, of which the following is a specification.

My invention relates to circular knitting 10 machines, and it consists particularly in improved means for properly controlling the extra thread commonly introduced for forming the high-splice and double-foot in seamless hosiery, as fully described in connection 15 with the accompanying drawing and specifically pointed out in the subjoined claims.

Figure 1 is a fragmentary sectional elevation of a portion of a circular knitting 20 machine having my improvements applied thereto.

Fig. 2 is a plan view of the cam block employed.

Fig. 3 is a view looking in the direction 25 of the arrow 3 Fig. 1, showing the free ends of the special extra thread carrier finger and an adjacent lowered one, and indicating the relative elevated positions of a long-butt and a short-butt needle.

Fig. 4 is a developed interior view of the 30 cam block, with needle courses indicated.

Fig. 5 is a detail view of the special high-splice thread carrier finger.

The drawing indicates a needle cylinder 5 of the rotary type, provided as usual with two series of vertically guided needles, 6 and 7, having respectively long butts 8 and short butts 9; a relatively fixed cam block 10 to which the needle-operating cams are fixed; 40 and a plurality of vertically swinging thread carrier fingers 12, 13. Other well known parts of the machine are omitted as unnecessary to the showing of my invention.

The cam block 10 is provided with the 45 usual pickers 15, 15, and fixedly inclined knitting cams 17, 17, coöoperating with inclines 18, 19 of the intermediate needle track cam 20 and main track 21, 21. Between the converging upper portions of the inclined 50 knitting cams 17, 17 I provide two needle lowering cams, one of which, 25, is fixed and adapted to engage and lower the long-butt needles only, while the other, 26, is horizontally movable having an outwardly extending shank 27 pivoted to the block at its

outer end 28 and adapting it to be engaged and swung by the short butt needles only. The fixed cam 25 has an extension 30 underlying the shank 27 of the inwardly projecting movable cam head 26; and the latter is 60 adapted to be swung by the contacting short-butt needles against the adjacent inclined knitting cam 17, so as to provide an extension of such fixed incline for smoothly lowering the short-butt needles. This position of the swinging cam, which is assumed in ordinary circular knitting, is shown in Fig. 4, where the course of the long-butt needles is indicated at 35, and of the short-butt needles at 36; and it is automatically 65 moved away from said fixed knitting cam 25 during reverse movement of the cylinder in reciprocating knitting, to coöperate with the fixed cam extension 30.

The long-butt needles being lowered first, 70 by contact with the fixed top cam 25, while the short-butt needles continue their elevated course until they have swung the movable cam 26 to its needle-lowering position, the divided short-butt needles may be supplied with thread for high-splicing or double-soling. In order that this may be done with certainty and accuracy I provide a special thread carrier adapted to properly present such special thread. A number of 75 pivotally movable thread carrier fingers as shown at 12, 12 in ordinary form, are commonly employed to throw determined threads into or out of knitting operation as

may be required for striping, etc.; and my 80 special carrier indicated at 13 is of similar form excepting as to its thread-guiding end. This special carrier 13, which remains in operative lowered position during the splicing operation, is provided with a thread 85 guide portion 39 which is operatively rigid with the main portion thereof but is capable of being varyingly set relative to the latter so as to permit of accurately positioning its thread outlet 40 relative to the thread outlet 90 of the adjacent carrier 12, when both are in fully lowered position, so as to insure uniform feeding of both threads to the divided short butt needles only. The integral and normally rigid connection 41 between this 95 thread guide portion 39 and the elevated outer portion 38 of the carrier 13, is capable of being twisted or wrenches so as to give a required relative set to the portion 39; and it extends laterally from said portion 38, as 100 105 110

shown, so as to locate the thread guide portion 39 in the swinging plane of the adjacent carrier 12 and thus further facilitates the proper co-operative positioning of the threads 5 irrespective of the swinging movements of the carriers.

What I claim is:—

1. In a knitting machine comprising a rotary needle cylinder provided with long-butts and short-butts needles and a plurality of thread carriers; a cam block provided with two top needle-lowering cams, one of which is fixed and adapted to operate on the long-butts needles only and the other of which is preliminarily moved by impact of the short-butts needles only.
2. In a knitting machine comprising a rotary needle cylinder provided with long-butts and short-butts needles and a plurality of thread carriers; a cam block provided with two top needle-lowering cams, one of

which is fixed and adapted to operate on the long-butts needles only and the other of which is preliminarily moved by impact of the short-butts needles only, said fixed cam 25 having a horizontal lower portion extending under the movable one.

3. In combination with a rotary needle cylinder provided with long-butts and short-butts needles, and a cam mechanism comprising fixed and movable needle-lowering cams, a plurality of swinging thread carriers one of which is provided with a thread-guide end portion having a rigidly-settable connection to the main portion adapted to permit relative positioning of the thread outlet independently of the bodily swinging movement, said relatively settable thread guide portion being arranged in the swinging plane of another of the carriers.

In testimony whereof I affix my signature.

FRANK W. ROBINSON.
